Wm. Simpson, Sons & Co., Inc., Philadelphia,
Pa., a corporation of Pennsylvania

Application March 26, 1952, Serial No. 19,059

Term of patent 7 years

(Cl. D92—1)

To all whom it may concern:

Be it known that I, Walter R. Cuddy, a citizen of the United States, residing in Douglaston, Queens County, State of New York, have invented a new, original, and ornamental Design for a Textile Fabric, of which the following is a specification, reference being had to the accompanying drawing, forming a part thereof in which:

Figure 1 is a face view of a piece of fabric, showing my new design; and

Figure 2 is an enlarged fragmentary sectional view on the line 2—2, Figure 1.

I claim:

The ornamental design for a textile fabric, as shown.

WALTER R. CUDDY.
